CLAIM

The ornamental design for a support bracket for poles
of circular cross-section, as shown and described.

DESCRIPTION

FIG. 1 is a bottom perspective view of a support
bracket for poles of circular cross-section showing my
new design;

FIG. 2 is a top plan view thereof;

FIG. 3 is a front elevational view thereof;

FIG. 4 is a side elevational view thereof, the opposite
side being substantially a mirror image; and

FIG. 5 is a rear end elevational view thereof.

Fig. 3
